BOWLING GAME

John L. Carroll, Baltimore, Md.

Application April 9, 1947, Serial No. 740,370

1 Claim. (Cl. 273—41)

1

This invention relates to entertainment equipment and more particularly to games of bowling and the like, especially those operating in conjunction with coin slot mechanism.

In the present forms of bowling games, the pins have to be replaced in position after being knocked over, by hand or by an independent mechanism arrangement that picks the pins up bodily, carries them to the proper location, then sets and releases them. The arrangement is cumbersome and involves many parts and expensive construction, and is not suitable for small, or household use. Also it does not avoid the necessity for extra help to pick up and return the balls.

It is therefore an object of the present invention to provide new and improved bowling game equipment that will avoid one or more of the disadvantages and limitations of the prior art.

Another object of the present invention is to provide new and improved bowling game equipment that will operate readily.

An additional object of the invention is to provide new and improved bowling equipment that will employ pin means subject to proper placement and positioning with a minimum amount of mechanism and have simple construction.

Other objects will become apparent as the invention is more fully set forth.

For a better understanding of the invention its principles, and its objects, reference is made to the appended drawings and the description following. These together illustrate a particular form of the invention by way of example, and not limitation, to make the operation, structure and functioning clear, while the claim points out the general scope of the invention.

In the drawings:

Figure 1 is a plan view of a bowling game embodying this invention; with part broken away to show the ball delivering mechanism;

Figure 2 is a side elevation of Figure 1, with parts broken away to show the internal construction and with the pin board shown in dotted outline in raised position;

Figure 3 is a front end view showing the ball delivery and coin slot mechanism; and

Figure 4 is a sectional view taken on line 4—4 of Figure 1, showing the pin board in raised position.

Similar reference numerals refer to similar parts throughout the drawings.

In the particular structure shown in the drawings, a framework 10, having supporting sides 11, forms the bed for an isolated bowling game unit.

2

The frame work 10 has a longitudinal runway 12 down which the balls 13 are rolled when propelled by the player, to knock over the pins 14. The pins 14 are made of flat material and are hinged at 15 to the playing field apron 16 so they will stay upright in one position and flat against the apron 16 in another.

The pins are placed in the conventional position usually used in American bowling. The playing field apron 16 of the runway where the pins 14 are situated is divided from the rest of the runway 12 by being hinged flush therewith at 17 in order to permit it to be angularly raised upward from the plane of the main runway 12.

15 This permits access to the underside of the runway and the mechanism used in raising the pins and to the return channel for the spent balls. Beyond the field apron 16 and attached to the frame 10 is a ball pen 18 into which the balls 13 are sent when they pass off the playing field. The bottom plate 19 of the pen 18 is tilted angularly in a downward direction to allow the balls 13 to run into the return channel 20 under the action of gravity. This channel is of cylindrical duct form and is slanted downwardly to the front of the framework 10 under the runway 12 where it is arcuately bent at approximately right angles into an apertured sleeve 21. This sleeve is covered underneath by a slider 22 that closes the aperture 23 normally, under the action of coiled springs 24. The balls 13 are of such size with respect to the channel 20 that they can roll down inside it without obstruction and easily turn the corner 25 of the arcuate part into the sleeve 21. They cannot fall through the aperture 23 until the slider 22 is moved out of the way to allow it.

20 A ball box 27 is located under the sleeve 21 to catch the balls 13 when they are dropped through the aperture 23 on the opening of the slider 22. The slider is opened when the link 28 is operated by a coin mechanism 29, when a coin 30 is inserted into it. The coin mechanism 29 is of the standard type which can only be operated 25 inwardly through the insertion of a coin. The balls 13 are removed from the box 27 through a hole 50 positioned in the front of frame 10.

The player takes the balls from the ball box 27 in threes when he is ready to play, and after 30 he has inserted the coin to make them drop therein for the purpose.

The flat pins 14 swing on their hinges 15 and are contacted by wire fingers 31 extending through slots 32 provided in the runway apron 16 when used for lifting the pins 14 from a hori-

zontal position to a vertical playing position. These wires 31 are relatively thin and require very narrow slots 32 to operate in so as not to materially affect the surface and action of the apron 16.

The wires 31 are attached to rod shafts 42 that are journaled in the bearings 33 mounted on the underside of the apron 16 so as to rotate therein in a direction suitable for operating the wires 31 in the slots 32. These shafts are rotatably operated together through the use of links 34 connected to them, from a main connecting bar 35 disposed under them. This bar 35 is operated through one of the shafts 42 having a crank like attachment 36 fastened to it. This attachment 36 is manually moved by a handle bar 37 pivotally connected to it and wires 31 are arranged in four rows to suit the conventional layout of the pins on the apron. The guiding eye bolt 38 and handle bar 37 are placed on the side wall of the framework 10. The bar 37 extends to the front where the player will have facile access to it. A spring keeps the handle bar, shafts and wires tensioned to their normal positions when the handle bar is not pulled out.

The coin mechanism consists of a flat slider 40 reciprocable in a channelled plate. The plate is formed to take a coin, such as a nickel, and align it with the slider, which in turn allows the coin to propel an element 42' that causes slider 40 to open the aperture 23 in the channel sleeve 21 and allow the balls 13 to fall down into the box 27. When this operation is performed, the coin falls through the channel plate into a money box 44. The coin mechanism returns back to its normal position under the tension of a spring. The apron 16 is kept down flat in the framework 10 and aligned with the runway. The apron 16 however may be moved up sufficiently to cause the pins to fall over into a position that will leave them erect when the apron is closed down to the runway level. It is believed that the operation of the device will be apparent from the above description and by inspection of the structure shown in the drawings. The form of the invention is such that it can be readily manufactured in small or large sizes and be just as entertaining to the users and onlookers. The pins can be set up so quickly, with such little effort and from the player's position, that it avoids the use of other usual necessary help employed for the purpose. This is especially the case with the picking up of the balls since the balls come back automatically.

While but one general form of the invention is shown in the drawings and described in the specifications, it is not desired to limit this application for patent to this particular form, as it is appreciated that other forms of construction could be made that would use the same principles and come within the scope of the appended claim.

Having thus described the invention, what is claimed is:

A game apparatus comprising a box-like framework having supporting sides, a bottom, and a bed above the bottom, said bed including a forward runway and a rearward playing field apron, said runway and apron having meeting edges substantially midway of the bed, hinges between the runway and the apron at the meeting edges thereof mounting said apron for vertical swinging movement to permit access to the space therebelow, a set of simulated bowling pins hinged to the playing field apron, said pins being normally in upright position and falling flat on the apron when struck from the front, the apron having a series of openings therethrough behind each pin, a plurality of parallel shafts, bearings for said shafts carried beneath the apron, a plurality of fingers carried by said shafts and rotatable therewith, said fingers being projectable through the aforesaid openings, means for interconnecting said shafts to rotate in unison, a crank on one of said shafts extending through one side of the framework, a handle connected to said crank and extending alongside of the framework towards the front thereof, a guiding eye bolt secured to the side of the framework and through the eye of which said handle extends, and spring means to maintain said handle in normal position.
